MERCURY VAPOR RECTIFIER TUBE
EMPLOYING MAGNETIC FIELD

John H. Coleman, West Palm Beach, Fla., assignor to Radio Corporation of America, a corporation of Delaware

Application October 30, 1952, Serial No. 317,709

6 Claims. (Cl. 313—161)

1

This invention relates generally to high-voltage mercury vapor rectifiers and more particularly to such rectifiers in which a magnetic field is impressed to produce electron trapping.

This invention specifically relates to an improved structure of a mercury vapor rectifier type of discharge device that has a low voltage drop on the forward portion of the cycle and an extremely high inverse voltage to prevent arc back.

This invention also is specifically designed to eliminate the slow switching limitations of mercury vapor type of rectifier device so that the device may be used at much higher frequencies.

It is therefore an object of this invention to provide a new and improved mercury vapor type of discharge device utilizing a magnetic field for electron trapping.

Another object of this invention is to provide a mercury vapor rectifier tube for high-frequency, high-voltage operation that will have a high inverse voltage rating.

A further object of this invention is to provide a novel mercury vapor rectifier tube utilizing an applied magnetic field and employing electron trapping to aid in the switching of an arc type discharge.

A still further object of this invention is to provide a new and novel mercury vapor type discharge device that utilizes an arc type discharge that may be rapidly switched on and off.

These and other objects are attained in accordance with the general aspect of this invention by providing a mercury vapor discharge device comprising a pair of spaced apart cathode plates, one normally being in contact with a mercury pool, and the other supporting an elongated igniter rod. Surrounding the elongated rod is a ring shaped anode. During operation, a magnetic field is applied parallel to the elongated rod for the purpose of trapping the electrons between the rod and the anode. The electron trapping, caused by the magnetic field and the electrode potentials, causes a large number of mercury vapor positive ions to be formed so that a glow discharge occurs between the rod and anode which immediately is transformed into an arc discharge between the mercury pool and the anode.

The above mentioned features and advantages, as well as many others, will be best understood by referring to the following descriptions of the illustrated embodiments when read in connection with the accompanying drawings wherein like reference characters designate similar parts throughout the several views and in which:

2

Figure 1 is a cross sectional view of an embodiment of this invention utilizing an ion accelerating gradient that it established toward the mercury pool;

5 Figure 2 is a cross sectional view of another embodiment of this invention.

Referring now to Figure 1, there is shown a cross-sectional view of one embodiment of this invention. Included in this view is a gas tight

10 enclosure which utilizes the elements of the structure, as shown, to form the gas tight enclosure. The enclosure includes a pair of substantially parallel spaced apart cathode disks 15 and 17. Separating these two cathode disks is

15 a hollow tubular insulating member 14. Inside the enclosure, and normally on cathode disk 17 is a mercury pool 18. Connected to cathode disk

16 is an elongated rod, or igniter electrode, 16. Substantially parallel to the two cathode disks

20 15 and 17 is an annular anode 11 supported by means of a rod, or wire 12 that is in turn supported in a recessed portion 13 of the insulating member 14 as shown.

The cathode disks 15 and 17 are sealed to the insulating member 14, as is the recessed portion

25 13, to form a gas tight seal so that mercury vapor will not escape from the enclosure. The conductive support rod 12 is sealed in the same manner to the recessed insulating member 13 as shown.

Any of the well known seals may be utilized to form the junctions between the various members.

Disks 15 and 17 are constructed of magnetic material such as Kovar. The insulating members 13 and 14 may be constructed of glass. The elements 11, 12, and 16 are preferably substan-

30 tially non-magnetic to prevent distortion of a magnetic field. Adjacent the cathode disks or plates 15 and 17 is a magnet 19 having a magnetic field substantially in the direction as is indicated by the arrow and letter H. It should be

35 understood that a circular type magnet may also be used however, it is desired to have the magnetic lines of flux pass through anode 11 substantially parallel to the igniter rod 16 as is shown. A recess portion 13, in insulating member 14, is for the purpose of eliminating sputtering of the mercury onto the insulating member 14 and thus to maintain the high voltage characteristics of the device. The lead-in wire, or rod, 12 should be rigid enough to support the anode 11 without permitting it to bend so as to touch the igniter electrode 16, or the mercury pool 18. It should be noted that igniter electrode 16 extends below the anode 11. This extension should be far enough so that the electric field of the igniter

40 electrode 16 appears to be infinitely long when

45 50 55

viewed by the anode 11. In order to do this the igniter electrode 16 must extend below the anode 11 a distance approximately equal to the radius of the anode 11.

In operation of this embodiment of my invention, a potential difference is applied between the igniter 16 and the anode 11. The potential difference causes electrons to be emitted from igniter 16 in a direction toward anode 11. Due to the magnetic field the electrons will travel in a curvilinear path and will thus produce a sufficient number of positive ions to cause a glow discharge to occur between these two electrodes. This phenomena is explained more completely in a copending application of mine Serial Number 93,824, filed May 14, 1949, now Patent Number 2,615,139. When the current through the tube from the glow discharge is of sufficient value, an arc discharge forms between the mercury pool 18 and the anode 11, resulting in a discharge that has a low arc drop and a very high current rating.

The rate at which the arc discharge occurs can be made to be consistent, as well as fast, if the part of the cathode formed by cathode disk 15 and igniter 16 is elevated slightly in potential above the portion of the cathode formed by cathode disk 17 and mercury pool 18. This occurs due to the deflection of a large portion of the positive ions, that are formed in the glow discharge, down to bombard the mercury pool 18. The potential adjustment between these elements is accomplished by means of a resistor 20 connected between the cathode disk 15 and cathode disk 17 as shown.

When the voltage is reversed, i. e. the inverse cycle for rectification, the arc is extinguished as electrode 11 is now negative with respect to the cathode disks 15 and 17, the igniter electrode 16, and the mercury pool 18. Because there is no electron trapping in the inverse portion of a cycle, i. e. when anode 11 and rod 12 are negative with respect to the other electrodes, no glow discharge will occur. When the anode swings positive again, on the forward portion of the cycle, electron trapping again results and the process is repeated.

Referring now to Figure 2, there is a cross-sectional view of an embodiment of this invention wherein an anode 21 is a washer shaped anode extending between the hollow tubular insulating members 24 and 30. Cathode disks 25 and 27 each have shielding members 22 inside the enclosure. The shielding members 22 are cylindrical and will normally contain the mercury pool 28. The purpose of these shielding members 22 is to prevent sputtering on the insulating members 24 and 30, and also to protect the glass-to-metal seals between insulating members 24 and 30 and cathode disk 27 from harmful effects of the mercury.

Since anode 21 extends through the enclosure it is especially well adapted for cooling. This is true because the outer circumference of anode 21 is exterior the enclosure and, if desired, fins or other well known cooling configurations may be placed on the outer circumference of the anode 21.

The other elements of Figure 2 are similar to those shown in Figure 1, as is the operation of the device, and further explanation of these elements or of the operation is not deemed necessary.

I claim:

1. A mercury vapor discharge device, comprising a gas tight enclosure, said enclosure com-

prising a pair of spaced apart cathode disks and insulating means intermediate the periphery of said disks, sealing means joining the ends of said disks and said insulating means in gas tight relation, a mercury pool within said enclosure and normally in contact with one of said disks, an elongated rod connected to the other of said disks and extending toward said mercury pool, said rod and said mercury pool normally being spaced apart, a ring shaped anode within said enclosure and spaced around said rod, conductive means supporting said anode and extending through said insulating means, and magnetic means adjacent said enclosure for applying a magnetic field parallel to said rod.

2. A mercury vapor discharge device, comprising a gas tight enclosure, said enclosure comprising a pair of spaced apart cathode disks and insulating means intermediate the periphery of said disks, sealing means joining said insulating means and said disks in gas tight relation, a mercury pool within said enclosure and normally being in contact with one of said disks, an elongated rod connected to the other of said disks and extending toward said mercury pool but normally being spaced therefrom, a ring shaped anode within said enclosure and spaced around said rod, a conductive rod connected to said anode and extending through said insulating means, and a magnet means adjacent said disks exterior said enclosure and so positioned with respect to said elements that the field of said magnet extends through said anode substantially parallel to said rod.

3. A mercury vapor discharge device, comprising a gas tight enclosure, said enclosure comprising a pair of spaced apart cathode disks and a pair of spaced apart hollow tubular insulating members intermediate the periphery of said disks, an anode plate extending between said insulating members on all sides and having a substantially round aperture therein, sealing means joining said insulating members to the periphery of said cathode disks and to said anode plate in gas tight relation, shielding means connected to said disks and extending toward said anode but spaced therefrom, a mercury pool within said enclosure and normally in contact with one of said disks and within said shielding means, an elongated rod extending from the other of said cathode disks through said aperture toward said cathode pool, said rod normally being spaced from said anode and said mercury pool, and a magnet having one pole adjacent each of said disks exterior said enclosure and so positioned with respect to said elements that the field of said magnet extends through said anode substantially parallel to said rod.

4. A mercury vapor discharge device, comprising a gas tight enclosure, said enclosure comprising a pair of spaced apart cathode disks and insulating means intermediate the periphery of said disks, said insulating means including a recessed portion, means joining said insulating means and said disks in gas tight relation, a mercury pool within said enclosure and normally being in contact with one of said disks, an elongated rod connected to the other of said disks and extending toward said mercury pool but spaced therefrom, a ring shaped anode within said enclosure and spaced around said rod, a conductive rod extending from said anode through said recessed portion, and a magnet having one pole adjacent each of said disks and so positioned with respect to said elements that the field of

said magnet extends through said anode substantially parallel to said rod.

5. A mercury vapor discharge device, comprising a gas tight enclosure, a pair of spaced apart cathode disks each having one surface within said enclosure, means to support said disks in spaced apart relationship, a mercury pool normally being in contact with one of said disks, an annular anode supported parallel to said disks intermediate thereof, an elongated igniter rod connected to the other of said disks and extending toward said mercury pool but spaced therefrom and through said annular anode, and means to apply a magnetic field to said device so that said magnetic field passes through said anode substantially parallel to said igniter rod.

6. A mercury vapor discharge device, comprising a gas tight enclosure, said enclosure comprising a pair of spaced apart cathode disks and insulating means intermediate the periphery of 20

said disks, sealing means joining the ends of said disks and said insulating means in gas tight relation, a mercury pool within said enclosure and normally in contact with one of said disks, an annular shaped anode within said enclosure intermediate said disks and substantially parallel thereto, means to support said anode extending through said insulating means and sealed thereto, an elongated rod connected to the other of said disks and extending through said anode toward said mercury pool but spaced therefrom, said rod being spaced within said anode and extending through said anode a distance substantially equal to the radius of said anode, and means to apply a magnetic field to said device so that said magnetic field will be substantially parallel to said elongated rod.
